UNITED STATES PATENT OFFICE.

EVERETT WARD, OF CRANFORD, NEW JERSEY.

CLEANING ATTACHMENT FOR PASTEURIZERS.

Application filed January 8, 1926. Serial No. 80,123.

The present invention is concerned with a device for cleaning Pasteurizer tanks and is particularly applicable to a cleaning attachment for coil Pasteurizers.

5 In the usual type of coil Pasteurizer in which a spiral steam coil is rotatably mounted in a round bottomed tank, it is very difficult to clean the tank walls under the coils. These walls are inaccessible for the ordinary type of hand brush, with the consequence that thick casein deposits frequently form thereon. In accordance with the present invention, I overcome this difficulty by the provision of a brush extending substantially the length of the tank, and detachably carried by the rotating steam coil. By rotating the coil, the brush sweeps the entire curved bottom of the tank under the coil, and effectively cleans the same. Means for 10 securing the brush to the coils preferably includes some mechanism for exerting a spring tension on the brush, whereby the same is firmly pressed into engagement with the surface to be cleaned.

25 Objects of the invention are to provide a device of this character which may be readily attached to, or removed from the coil of a Pasteurizer, a device in which the brush is dragged, rather than pushed, over the whole 30 surface, a cleaning attachment which will be simple, practical and durable in construction, comparatively inexpensive to manufacture, and highly efficient in use.

With the above noted and other objects in view, the invention consists in certain novel features of construction and combinations and arrangements of parts, as will be more fully hereinafter set forth and pointed out in the claims. The invention may be 40 more fully understood from the following description in connection with the accompanying drawings, wherein—

Fig. 1 is a broken view in longitudinal section through a coil Pasteurizer showing my improved cleaning attachment in applied position.

Fig. 2 is a transverse sectional view on the line 2—2 of Fig. 1.

Fig. 3 is an enlarged sectional detail on the line 3—3 of Fig. 1.

The Pasteurizer shown is of conventional construction, including a tank 10 formed with a curved bottom wall 11 concentric with a helical steam coil 12 rigidly supported from a central steam supply pipe 13 by radial

braces 14. The supply pipe 13 is journaled in bearings 15 in the end walls of the tank, and may be rotated in any desired manner to revolve the steam coil and effect heating and agitation of the milk to be Pasteurized. 60

The device of the present invention is a cleaning attachment including a brush 16 adapted to be supported from two or more convolutions of the steam coil in such a manner that it is held under tension against the tank walls, and when the steam coil is revolved, cleans said walls. 65

I have shown the brush supported at two points from the coil 12. Inasmuch as these supporting means are identical, a description of one will suffice for both. It will be noted that the support includes a spring collar 17 lined with leather or other suitable material 18, which will tightly grasp a coil convolution. One end of the collar pivotally carries a clamping screw 19 provided with a wing nut 20. The other end of the collar is riveted or otherwise secured to a casting 21, said casting including bifurcated arms 22 adapted to straddle the clamping screw 19, whereby when the wing nut is moved down to bind against the arms 22, collar 17 will be contracted and the coil convolution 23 which it embraces, will be tightly gripped. 70 75 80 85

The casting 21 also includes an off-set portion 24, normally disposed in horizontal position when the clamps have been attached, this portion 24 serving to anchor the end 25 of a spring member 26 carrying and exerting tension on the brush 16. As seen best in Figs. 2 and 3, the spring member 26 bows upwardly away from the clamp, and then curves back, terminating in a trailing end disposed approximately under the clamp, so that a wide resilient arm is provided for dragging the brush over the tank walls. The spring terminates in a right angularly disposed downwardly presented finger 27 100 adapted to be clamped between the back 28 of the brush 16 and a warping strip 29 held to said back by bolts 30. A similar warping strip 31 mounted upon the opposite side of the back 28 is removably secured by the same bolts, and serves to conveniently clamp the upright arm 32 of an L-bracket 33 against the back. Arm 32 is provided with a slotted opening 34 receiving the spring 26 and effectively locking the finger 27 against 110

accidental withdrawal from its position between the warping strip 29 and brush back 28.

It is to be understood that I have shown the spring 26 as one efficient and suitable means for exerting tension on the brush 16 to maintain the same firmly pressed against the wall of the Pasteurizer as the steam coil revolves. It will be evident however, that I might resort to numerous alternative expedients in this connection. Various other types of springs might be employed, and various other constructions used to effect supporting of the brush and the exerting of spring pressure thereon to force it against the tank.

The manner of using the attachment is substantially as follows. Immediately after milk has left the Pasteurizer, the tank is flushed with cold water, then partially filled with warm water and a cleaning solution such as oakite. The coil is run for ten minutes to thoroughly agitate the oakite and cause it to lave the coil and tank walls. This solution readily softens and dissolves the casein deposits on the steam coil and on the tank walls. The brush is then secured in position by the simple expedient of wrapping the clamps 17 about spaced convolutions of the steam coil, and screwing the wing nuts home. The coil is again rotated and the tank effectively cleaned. It may be noted that the rate of rotating the coil may be as high as 38 R. P. M., so that the cleaning operation will be quickly performed.

Various changes and alterations might be made in the general form and arrangement of parts described, without departing from the invention. Hence I do not wish to limit myself to the details set forth, but shall consider myself at liberty to make such changes and alterations as fairly fall within the spirit and scope of the appended claims.

I claim:

1. A cleaning attachment for coil Pasteurizers including an elongated brush, spring arms detachably secured at spaced points to the brush and adjustable clamping collars carried at the ends of the arms adapted to engage convolutions of the rotating coil of a Pasteurizer.

2. A cleaning attachment for coil Pasteurizers including an elongated brush member, warping strips detachably secured at opposite sides to the back of the brush, spring arms including laterally disposed fingers clamped between one warping strip and the brush back, and adjustable clamping collars carried at the ends of the arms and engageable with the rotating element of a Pasteurizer.

3. A device of the class described in claim 2, wherein brackets clamped between the other warping strip and the opposite side of the brush back, engages the spring arms to prevent displacement of the angularly disposed fingers.

EVERETT WARD.
